UNITED STATES PATENT OFFICE.

WALTER MAUD, OF SYRACUSE, NEW YORK, ASSIGNOR OF ONE-HALF TO ORMAN H. MAUD, OF SYRACUSE, NEW YORK.

ADJUSTABLE FOOT GUARD.

Application filed September 6, 1927. Serial No. 217,690.

This invention relates to an improved foot-rest, designed especially for supporting the foot of the driver of an automobile that controls the gas-accelerator, and has 5 for its object to provide a rest or support of the class, which may be mounted upon the deck of the automobile adjacent the pedal of the accelerator, for preventing accidental shifting of the foot out of contact 10 with the pedal. A further object is to provide a foot-rest comprising an elongated base, which may be rigidly secured to the deck, upon which is mounted a guard formed with a socket adapted to receive the 15 heel of the driver's shoe; the said guard being adjustable on the base for accommodating feet of different length; the said base being formed with a longitudinal slot and with a number of spaced sockets; the 20 heel-guard being loosely attached to the base by means of a guide-bolt, which is arranged to traverse the said slot when the guard is moved along the base; and the guard being formed with a depending stop, which is ar- 25 ranged to engage the sockets formed in the slot, for holding the guard in the various adjusted positions. The guide-bolt is so constructed that the guard cannot rotate, but may be raised manually for freeing the 30 stop from the base, for enabling the guard to be freely moved towards and from the pedal.

I attain these objects by the means set forth in the detailed description which follows, and as illustrated by the accompanying drawing, in which—

Figure 1 is a broken sectional view of the dash and deck of an automobile, showing the foot accelerator pedal; also showing the application of my improvement. Fig. 40 2 is an enlarged side elevation of the foot-support. Fig. 3 is a central vertical longitudinal section taken on line 3—3 of Fig. 4. And Fig. 4 is a top plan view of the com- 45 plete device.

In the drawing, 2 represents the dash and 2^a—2^b the inclined and the level portions of the deck of an automobile. 3 represents conventionally the pedal of the ordinary 50 foot accelerator, which is pivoted at 3', and may be rocked forwardly by the weight of the driver's foot, as A, for accelerating the feed of the fuel-gas, in a well-known manner.

My foot-rest is arranged to be rigidly 55 mounted upon the inclined deck portion 2^a, as shown in Fig. 1, and preferably comprises an elongated metal body 4, having legs 4', which space the body from the deck, and having perforations 4^a to receive attaching 60 screws 5. The body 4 is slotted longitudinally, as at 4^b, and said slot is formed at intervals with enlargements or sockets 4^c.

6 represents the movable guard or member of the rest, which comprises a substantially 65 semi-circular body having an upwardly facing socket 6' defined by a flange 6^a, said socket conforming to the shape of the heels of ordinary footwear. The bottom 6^b of the socket 6' is preferably stepped downwardly towards its open end for providing ledges, as 6^c, to be engaged by the heels for suitably positioning one's foot relatively to the pedal 3. The forward end of the guide 75 6 is provided with a countersunk opening 6^d to receive the head of a bolt, as 7, the body of the bolt preferably being square in cross-section and loosely engaging the slot 4^b, in which the bolt is slideable, for adjusting the guard 6 relatively to the pedal 3, as best 80 seen in Fig. 3. The lower end of the bolt is formed with a flange 7', which is considerably broader than the slot 4^b, and said flange is preferably normally spaced from the underside of the body 4 when the guard 85 is in the operative position, shown in Figs. 1, 2 and 3. The bottom 6^b is formed with an integral depending stop-lug 6^c, which is arranged to register with and to engage the sockets 4^c, for holding the guard in various 90 adjusted positions, as shown in Fig. 3. At the rear end of the guard the flange 6^a extends a considerable distance below the stepped-portion 6^b, and is formed with a horizontal slot 6^e, in which the base 4 loosely 95 plays, the said slot being of sufficient depth to enable the guard to be lifted manually sufficiently to free the stop 6^c from the sockets 4^c, for enabling the guard to be moved in either direction along the body 100 4, for holding the foot A in the proper relation to the pedal 3. Minor adjustments to suit shoes whose length varies but slightly, as well as for disposing the feet in more restful positions, may be effected by shifting 105 the heels forwardly or backwardly and allowing them to rest against the shoulders of the ledges 6^c. Ordinarily, gravity sup-

plements the stop 6^e for holding the guard in the adjusted positions, whether or not pressure is exerted by the driver's foot.

My invention is extremely simple and may be constructed and applied at small expense and with a slight amount of labor. By providing a number of the sockets 4^e, the guard 6 may be readily and quickly adjusted for footwear of many different sizes, and there is no danger of the driver's foot straying from the pedal 3.

Having thus described my invention, what I claim is—

1. A foot rest comprising an elongated base having a longitudinal slot intersected by a number of spaced sockets, a heel-guard slidable on said base, said guard having means adapted to engage said sockets for holding the guard in various positions relatively to the pedal of a foot accelerator.

2. A foot rest adapted to be mounted adjacent the accelerator of an internal combustion engine, comprising a base having a longitudinal slot and a row of spaced sockets for gaging the length of the operator's foot, a heel guard slidable on said base towards and away from the pedal of the accelerator, said guard being loosely connected to the base by a member that plays in said slot, and having means to engage said sockets for holding the guard in different positions relatively to the pedal.

3. A rest for the foot of the driver of an automobile that controls the foot accelerator, comprising an elongated slotted base adapted to be mounted on the deck of the automobile adjacent the pedal of the accelerator, sockets formed in the

base adjacent said slot, a heel-guard having a slot for receiving said base, means for loosely connecting the guard to the base adapted to traverse said slot, and means carried by said guard adapted to selectively engage the sockets of the base for supporting feet of different length relatively to said pedal.

4. A foot rest comprising a base adapted to be mounted on the deck of an automobile adjacent the pedal of a foot accelerator, said base being formed with a longitudinal slot, a bolt for loosely connecting the guard to the base, said bolt engaging and traversing said slot, a heel-guard mounted on said base and movable towards and from said pedal for gaging feet of different size the rear end of the guard being slotted to loosely receive the base, the forward end of the guard being loosely connected to the base by a bolt that traverses the slot of the base, and means carried by the guard adapted to engage said sockets for holding the guard stationary when adjusted.

5. A foot rest adapted to be mounted adjacent the foot accelerator of an internal combustion engine, comprising a base having a longitudinal slot and a row of spaced sockets for gaging the length of the operator's foot, a heel-guard slidable on said base said guard being loosely connected to the base by a bolt that traverses said slot and having means adapted to engage said sockets for holding the guard in different positions relatively to the pedal of the accelerator.

In testimony whereof I affix my signature.

WALTER MAUD.
